PUMP JACK

Fred D. Gunsaulus, Pampa, Tex., assignor of
one-half to Letitia Gantz, Pampa, Tex.

Application November 20, 1937, Serial No. 175,724

2 Claims. (Cl. 74—103)

This invention relates generally to pumps and more particularly to pump jacks.

An object of the present invention is to provide for the operating in an improved manner a vertically moving pump rod, or as otherwise known, a polish rod, and to that end embodies a novel and practical arrangement of pulley wheels over which the operating cable for the polish rod is trained, and an equalizing device for distributing equal stress to the cable so that the cross head connected to the cable will be supported in a true horizontal transverse position preventing side whip or lash of the polish rod when the pump is in operation.

The invention together with its objects and advantages will be best understood from a study of the following description taken in connection with the accompanying drawings wherein:

Figure 1 is a side elevational view illustrating the application of the invention.

Figures 2 and 4 are detail sectional views taken substantially on the lines 2—2 and 4—4 respectively of Figure 1.

Figure 3 is a fragmentary detail view partly in section and partly in elevation suggesting two positions which the uppermost pulley wheels may assume.

Figure 5 is a fragmentary top plan view showing the equalizing device, and

Figure 6 is a perspective view of the cross head.

Referring to the drawings by reference numerals it will be seen that in accordance with the present invention there are provided a pair of sills 7, 8 on which is mounted a frame comprising a pair of beams 12 which at one end are connected by a transverse beam 13 that is disposed in spaced parallelism to a transverse beam 14.

Suitably supported on the sill 8 and rising therefrom between the beams 13 and 14 are short posts 15 to which are pivoted as at 15' standards 16.

As shown in Figure 2 the standards 16 converge toward one another at their upper ends 45 and intermediate their ends are braced by a cross member 17.

At the upper ends thereof the standards 16 merge into a bearing 18 in which is fitted a shaft 19 on the opposite ends of which are grooved pulley wheels or sheaves 20.

For supporting the standards 16 in a vertical position as shown in Figure 3 there are provided props 21 which at their upper ends are pivoted as at 22 to the bearing-equipped ends of the 55 posts or standards 16. At the lower ends thereof

the props 21 are adapted to be detachably connected as at 23 to ears 24 that extend upwardly from the upper ends of standards 25 rising from the beams 12.

Props 21 are somewhat in the nature of turnbuckles as shown in Figure 3 so that said props may be longitudinally adjusted for positioning the standards 16 in a position of adjustment as will insure the maintaining of the polish rods perpendicular at all times.

The standards 25 which are relatively short are braced through the medium of diagonal braces 26 and at their upper ends are suitably provided to accommodate therebetween a shaft 27 on which are mounted a pair of grooved pulley wheels or sheaves 28.

Trained over the sheaves or pulley wheels 28 and 29 are opposite end portions of a cable 29 the terminals of which are adapted to be connected in any suitable manner with headed studs 20 provided on the relatively opposite ends of a cross head 31.

The cross head 31 is provided with an opening 32 to accommodate the polish rod 33.

As shown in Figure 2 the polish rod 33 has 25 clamped thereon above the cross head 31 a collar 34 composed of a pair of complementary sections which at their lower ends are provided with extensions 35 that are accommodated in a recess 36 provided therefor in the upper end of the opening 32. Also clamped on the polish rod 33 below the cross head 31 is a suitable clamp 37. Thus it will be seen that the cross head is accommodated between the collars 34 and 37 so that vertical movement of the rod 33 relative to the 30 cross head 31 is positively prevented.

The shackle rod of the drilling apparatus is indicated by the reference numeral 38 and at one end thereof the shackle rod 38 is connected with the cable 29 through the medium of an equalizer 40 indicated generally by the reference numeral 39. The equalizer 39 comprises a pair of substantially triangular plates 40—40 that are secured together in spaced relation through the medium of a bolt 41 and a spacing sleeve 42.

Rotatably supported between the plates 40 at the widest ends of the plates are pulleys or sheaves 43 over which is trained an intermediate portion of the aforementioned cable 29.

At one end thereof the shackle rod 38 is provided with an eye that is accommodated between the smallest ends of the plates 40 and through the medium of said eye and bolt and nut means 44 said end of the shackle rod is connected with the plates 40 of the equalizer device.

55

- For use as a safety stop for the shackle rod there is disposed on said rod 38 a clamp 45, the clamp 45 being disposed on the rod nearest to the eye-equipped end thereof, and the stop 45 may be secured on the rod 38 at the desired position of adjustment, and acts as a safety stop in case of breakage of power appliances and also to prevent a longer stroke than provided for at the cross head 31.
- 10 The shackle rod 38 also works through a guide 46 mounted on and supported between the beams 12, and suitably journaled within the guide 46 is a pulley or sheave 47 in the groove of which the shackle rod 38 is accommodated as clearly shown 15 in Figure 4.

As is well-known the shackle rod 38 is connected with the usual power unit for the pump jack through the medium of a rod or cable and to which rod or cable one end of the shackle rod 38 20 is connected through the medium of a turn-buckle the adjusting screw of which is shown in the drawings and indicated by the reference numeral 47, and which turn-buckle has the screw thereof provided with an eye through the medium 25 of which and a bolt 48 said turn-buckle screw is connected with a swivel 49 on the end of the shackle rod 38 as shown.

Also the shackle rod 38 at the swivel equipped end 49 thereof is equipped with a stop member 30 50, in the form of a two-part clamp and which is adapted to engage and abut the guide 46 in the event there be any breakage in the connection between the shackle rod 38 and the power unit.

It is obvious that in actual practice drive from 35 the power unit is transmitted to the shackle rod 38 causing the latter to reciprocate, and this reciprocatory movement of the rod 38 is transmitted to the equalizer 39, and from the equalizer 39 through the cable 29 to the cross head 31 for 40 alternately lowering and raising, or in other words reciprocating the polish rod 33.

The equalizer 39 will serve to equalize uneven 45 stress caused by wear on the cable 29 and will assure even and equal lift, stress or pull on the ends of the cable secured to the cross head and will further assure perfect vertical pump rod lift since the cross head will always remain in a substantially perfect level horizontal position thereby preventing transverse motion or side lash being 50 imparted to the polish rod.

It will also be seen, from a study of Figure 3, that when it is desired to repair the pump or well or to remove rods or tubing, the end of the props 21 may be disconnected from the exten-

sions 24 of posts 25 thus permitting the standards 16 together with the props 21 to be swung from the full line position to the dotted line position shown in Figure 3.

It is thought that a clear understanding of the 5 construction utility and advantages of an invention of this character will be had without a more detailed description.

Having thus described the invention what is claimed as new is:

1. In a pump jack of the class described, a frame, upper and lower pairs of pulleys carried by the frame, a cross head connected with the pump rod, a flexible member having its ends connected with the ends of the cross head, the two parts of the flexible member passing upwardly over the upper pair of pulleys and then downwardly under the lower pair of pulleys, a supporting member, a pulley carried thereby and around which the flexible member passes, a reciprocating rod supported for horizontal movement on the frame and having one end connected with the supporting member, means for reciprocating the rod, a guide on the frame through which the rod passes, a grooved sheave in the 15 guide, through the groove of which the rod passes, and adjustable stops on the rod, one on one side of the guide and the other on the opposite side of the guide.

2. A pump jack of the class described comprising a frame horizontally arranged, an upright frame having its lower end pivotally supported from the horizontal frame, a pair of pulleys carried by the upper end of the upright frame, a pair of short uprights carried by the 20 horizontal frame in rear of the first upright frame, a pair of pulleys carried by the short uprights, a cross head connected with the pump rod, a flexible member having its ends connected with the ends of the cross head, and the two parts of the flexible member passing upwardly over the pulleys of the first-mentioned upright frame and under the pulleys of the short uprights, an equalizer device including a pulley around which the bight of the flexible member passes, a reciprocating rod connected with the equalizing device, means for reciprocating said rod, a brace, means for adjusting the length of the brace, means for pivotally connecting the upper end of the brace to the upper end of the upright frame, and means for detachably connecting the lower end of the brace to the short upright members.

F. D. GUNSAULLUS.
